UNITED STATES PATENT OFFICE.

JOSEPH D. COUGHLIN, OF DORCHESTER, MASSACHUSETTS, ASSIGNOR TO SUPERIOR TOGGLE COMPANY, INC., OF BOSTON, MASSACHUSETTS, A CORPORATION OF MASSACHUSETTS.

TANNER'S TOGGLE.

1,084,539.

Specification of Letters Patent.

Patented Jan. 13, 1914.

Application filed May 8, 1913. Serial No. 766,427.

To all whom it may concern:

Be it known that I, JOSEPH D. COUGHLIN, a citizen of the United States of America, and a resident of Dorchester, in the county 5 of Suffolk and State of Massachusetts, have invented certain new and useful Improvements in Tanners' Toggles, of which the following is a specification.

This invention relates to devices for 10 stretching leather to which has been applied a coating of patent leather preparation, and which it is desired to thoroughly dry while the leather is stretched on suitable frames. These devices are commonly known to the 15 trade as single toggles.

Several forms of single toggles have heretofore been constructed but all of them are 20 objectionable either on account of the expense or their inability to secure the cord thereof sufficiently to prevent it from slipping through the cross member forming a part of said toggle.

The object of the present invention is to 25 obviate these objections and produce an inexpensive device of this class in which the cord is securely clamped to the cross member and it consists in two wires twisted together to form the cross member with a cord clamped securely between said wires intermediate their ends.

The invention further consists in certain 30 novel features of construction and arrangement of parts which will be fully understood by reference to the description of the drawings and to the claims hereinafter given.

Of the drawings: Figure 1 represents an 35 elevation of a toggle embodying the principles of the present invention. Fig. 2 represents an elevation of a cord having a loop formed in one end thereof. Fig. 3 represents a perspective view of said cord showing 40 a wire passed through its loop. Fig. 4 represents a side elevation of said cord showing two wires one through said loop 45 and another positioned parallel thereto at right angles to the crossing of said cord. Fig. 5 represents a plan view of the same. Fig. 6 represents a view similar to Fig. 4 with the wires twisted, and Fig. 7 represents a plan view of the completed toggle 50 showing the cross member thereof formed of said twisted wires.

Similar characters designate like parts

throughout the several figures of the drawings.

55

In the drawings, 10 is a cord or twine in which near one end is formed a loop 11, portions of said cord in the formation of said loop crossing each other at 12. Through the loop 11 is passed a short wire 13 and outside of said loop 11 opposite and at right angles to said crossing 12 is positioned a wire 14 parallel to the wire 13 and of the same length. When the wires 13 and 14 have been thus positioned relative to the loop 11 the ends of both wires are seized and twisted tightly together as indicated at 15 in Figs. 1, 6, and 7, thereby clamping the cord or twine 10 so firmly between the wires as to absolutely prevent it slipping relative thereto. It is obvious that, in the twisting of the wires 13 and 14 they will form a plurality of bights or bends in the cord which will have the effect of holding said cord in position even under the greatest strain. This 65 makes a most effective toggle which may be constructed at slight cost and will be sufficient to withstand any strain that it may be desired to give in the stretching of the leather to which it is applied.

70

One advantage of this device is that the cross member 15 being free from all projections is adapted to lie flat upon the leather being stretched, and, moreover, only very small holes need to be punctured in the edge 75 of the leather for the insertion of the cord 10. The cross member 15 being made of twisted wires has an uneven periphery which obtains a better grip upon the hide or leather while being stretched. When in 80 operation the cord 10 is passed through a hole in the leather to be stretched and is secured to the usual stretching frame in any well known manner.

85

The many advantages of a toggle constructed as herein shown and described will 90 be fully apparent without further description.

95

Having thus described my invention, I 100 claim:

1. A new article of manufacture consisting of a cord and two metal members on opposite sides of an end thereof and twisted together.

2. A new article of manufacture consisting of two metal members twisted together

105

with an end of a cord twice passed between said members and clamped thereby.

3. A new article of manufacture consisting of a cord having a loop formed in one end, a wire inserted through said loop, and another wire at right angles to and outside the crossing of said cord, said wires being twisted together.

4. A new article of manufacture consisting of two short wires twisted together and a cord clamped between said wires intermediate the ends thereof.

5. A new article of manufacture consisting of two short wires of equal length twisted together from end to end and hav-

ing clamped between said wires the end of a cord of relatively greater length than said wires.

6. A new article of manufacture consisting of a plurality of metal members twisted together and a cord having one end thereof passed twice between said members and clamped thereby.

Signed by me at 4 Post Office Square, Boston, Mass., this 14th day of April, 1913. 25

JOSEPH D. COUGHLIN.
